UNITED STATES PATENT OFFICE.

DANIEL F. MACCARTHY, OF WHITE BEAR, AND HARRY M. DARLING, OF ST. PAUL, MINNESOTA, ASSIGNEES, BY DIRECT AND MESNE ASSIGNMENTS, TO DARMAC COMMUTATOR COMPANY, OF ST. PAUL, MINNESOTA, A CORPORATION OF MINNESOTA.

IGNITER FOR GASOLENE-ENGINES.

No. 926,202.

Specification of Letters Patent. Patented June 29, 1908.

Application filed February 16, 1906. Serial No. 301,342.

To all whom it may concern:

Be it known that we, DANIEL F. MACCARTHY and HARRY M. DARLING, citizens of the United States, residing at, respectively, 5 White Bear and St. Paul, in the county of Ramsey and State of Minnesota, have invented certain new and useful Improvements in Igniters for Gasolene-Engines, of which the following is a specification.

10 Our invention relates to improvements in igniters for gasoline engines, its object being to provide a more positively acting igniter than the ordinary make-and-break or jump spark.

15 To this end our invention consists in the features of construction and combination hereinafter particularly described and claimed.

In the accompanying drawings forming 20 part of this specification, Figure 1 is a side view of our improved igniter partly broken away and showing the wiring conventionally; Fig. 2 is a section on line x—x of Fig. 1, and Fig. 3 is a face view of the contact disk forming part of the invention.

In the drawings 2 represents the governor shaft of a four cylinder engine. Secured upon the governor shaft as by means of screws 3 is a disk 4 of suitable conducting 30 material with a non-conducting facing 5. Projecting inwardly through the facing 5 from the outer edge of the disk 4 is a contact lug 6.

7 represents a lever arm of non-conducting 35 material loosely mounted upon the governor shaft and held against the inner face of the disk 5 by a collar 8. The collar 8 is suitably supported upon the shaft as by means of the screws 9. Slidable in sleeves 10 fitting in 40 openings through the lever 7 at a distance from the shaft 2 equal to that of the contact lug 6 are blocks 12, each having a concaved inner face into which loosely fits a ball 13. The free ends of springs 14 secured by 45 screws 15 to the outer edge of the lever, bear against the outer ends of the blocks 12. The secured ends of the springs carry binding posts 16. As shown in Fig. 1 the posts 16 are connected by wiring through a spark coil 50 box 17 with the ordinary spark plugs 18 of the engine. The wiring, spark coil box and spark plugs being the usual parts of an ordinary gasoline engine, are merely shown conventionally. The lever 7 may be secured in

adjusted position in connection with a suitable rack 19 to advance or retard the spark.

In operation the disk will rotate with the shaft 2, the lever 7 standing in the desired adjusted position. As the lug 6 passes over the balls 13, the primary circuit will be made 60 through the disk 4, contacting ball 13, block 12, binding post 16 and by the connected wiring through the spark coil box and battery. This will affect the secondary circuit of the spark plug in the ordinary way to 65 make a spark. Each complete rotation of the shaft 2 and disk 4 will thus successively affect the circuits of the four spark plugs to explode the charges in the four cylinders of the engine. The spark may be advanced or 70 retarded by adjusting the lever 7 in connection with the rack 19.

While in the drawings the igniter is shown arranged for a four cylinder engine it will be apparent that it can be used for a one or 75 more cylinder engine of two or four cycle type by using the appropriate number of contact blocks 12, and connected spark plugs. Also the disk 4 and lever may be mounted upon the governor shaft as shown, 80 or upon any other equivalent rotating part.

We claim:

1. An igniter of the class described comprising in combination with a rotary shaft, a non-conducting disk supported upon said 85 shaft, a contact electrically connected with said shaft and extending through the side face of said disk, a non-conducting rocker arm pivotally supported upon said shaft against the side face of said disk, a contact 90 block extending through and projecting from the face of said arm into the path of the contact carried by said disk, and a contact spring bearing against the outer end of said block. 95

2. An electric igniter of the class described comprising in combination with a rotary shaft, a non-conducting disk fixed upon said shaft, a contact electrically connected with said shaft and extending through the side 100 face of said disk, a non-conducting rocker arm pivotally supported upon said shaft against the side face of said disk, a spring pressed contact block extending through said arm, and a contact ball carried by the 105 end of said block and projecting from the face of said arm into the path of the contact carried by said disk.

3. An electric igniter of the class described comprising in combination with a rotary part, a non-conducting disk carried thereby, a contact carried by said disk and extending through the side face thereof, a non-conducting rocker arm pivotally supported upon said rotary part in contact with the side face of said disk, contacts extending slidably through said rocker arm and projecting from the face thereof into the path of the contact

carried by said disk, and contact springs bearing against the outer ends of said slideable contacts.

In testimony whereof we affix our signatures in presence of two witnesses.

DANIEL F. MACCARTHY.
HARRY M. DARLING.
